DESIGN.

—o—
N. KOMORI.

CARPET.

No. 17,852.

Patented Nov. 1, 1887.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,852, dated November 1, 1887.

Application filed August 30, 1887. Serial No. 249,322. Term of patent 31 years.

To all whom it may concern:

Be it known that I, NORIC KOMORI, of New York city, in the county and State of New York, have invented a new and original Design 5 for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design comprises a body portion and a border, E.

The body portion consists of several figures, 20 which are grouped or disposed upon the face of the carpet, as shown.

Figure A is a flower and leaf group having a large circular flower at its upper and middle portion, with pointed leaves radiating from the center. On one side of this central flower 25 is a similar flower form less prominent and partly underlying the former. On the other side of the figure is another flower form. Beneath these flowers are leaves, below which project a series of stems. Several smaller circular flowers appear among the leaves, and at 30 the top and sides of the figure there are projecting stems supporting bulbs or blossoms.

Figure B is a smaller group having a prominent circular flower with pointed radiating 35 leaves at one side. At the center of the figure there are several smaller flower forms, around and under which is a body-work of leaves. Stems project from the lower side bearing separate leaves and small flowers. Other stems 40 project from the top supporting bulb-like forms.

Figure C is a group of flowers and leaves and stems having a prominent flower form at the top with its leaves clearly marked, and 45 around this several smaller flower forms, some showing a top or face view of the flower, others a side view. At the left of the figure is another small flower form supported on a stem.

Leaves are spread out underneath the flowers, and stems project from the group, some supporting bulb forms. 50

Figure D is a triangular-shaped group having a large central flower form with pointed radiating leaves. On one side are two other smaller flower forms, one partly hidden. Another small flower form is shown on the other side. The flowers are supported on a body-work of leaves and stems, some of the latter bearing bulbs or small flowers. 55

The border E has an inner margin of small 60 ornamental work. The middle portion of the border consists of a stem having several branches, some branches supporting large circular flower forms and smaller circular flowers and leaves like those of the body portion, and 65 other branches bearing small circular flowers and buds and leaves. A few of the small circular flowers are scattered separately here and there between the stems. The outer margin of the border is ornamented with an irregular 70 stem-work here and there of a scroll-like form, bearing groups of long-pointed leaves. This outer margin is crossed by lines or bands of color.

What I claim as new, and desire to secure by 75 Letters Patent, is—

1. In a design for carpets, the figure A, substantially as shown.
2. In a design for carpets, the figure B, substantially as shown. 80
3. In a design for carpets, the figure C, substantially as shown.
4. In a design for carpets, the figure D, substantially as shown.
5. In a design for carpets, the figures A, B, 85 C, and D, substantially as shown.
6. In a design for carpets, the border E, substantially as shown.
7. The design for carpets, consisting of the figures A B C D and the border E, substantially 90 as shown.

NORIC KOMORI.
